UNITED STATES PATENT OFFICE

2,613,523

LOCK MECHANISM FOR WINDOW LATCHES

Neil O. Holmsten, New Rochelle, N. Y.

Application April 23, 1949, Serial No. 89,184

1 Claim. (Cl. 70—89)

1

This invention relates generally to latching means for swinging windows or glass doors. More specifically, the invention relates to a locking means to be used in conjunction with a pivoted latch, such as is used on French windows.

The invention is especially designed for application to standard type pivoted latches which are already in use for holding swinging windows and doors closed. Latches of this type are attached to the inside of a window or door and are quite effective for holding them closed, but it is a relatively simple matter for an unauthorized person to release the latch and open the window, or door, to which it is applied, to gain entrance to a building. It is only necessary to break a window pane or remove a small section thereof, or cut a small hole through a door, and then reach in from the outside and release the latch after which the window or door may be opened.

This invention, as disclosed herein, is adapted to be applied to either single or double swinging or sliding windows or doors and comprises a pivoted hasp or like member which is pivotally connected to a window or door jamb and is adapted to be swung into or out of engagement with a pivoted latching member carried by a window or door. A key-operated or combination locking means is provided to lock the hasp in engagement with the latching member when the latching member is in latching position and thus prevent releasing of the latching member by unauthorized persons.

The principal object of the invention is to provide an improved locking mechanism for application to swinging windows or doors to be used in conjunction with standard type latching means thereon.

Another object of the invention is to provide a locking mechanism of this type, which is of simple construction, efficient in operation and which is relatively inexpensive to manufacture.

Other and more limited objects of the invention will be apparent from the following specification and the accompanying drawings forming a part thereof wherein:

Fig. 1 is a front elevation of one embodiment of my invention showing it applied to a French window, with the various parts in locking position;

Fig. 2 is a horizontal section taken on the line 2—2 of Fig. 1;

Fig. 3 is a central vertical section taken on the line 3—3 of Fig. 1;

Fig. 4 is a view similar to Fig. 3 showing the locking mechanism in unlocked position;

Fig. 5 is a horizontal section taken on the line 5—5 of Fig. 1;

Fig. 6 is a vertical section taken on the line 6—6 of Fig. 4; and

Fig. 7 is a horizontal section taken on the line 7—7 of Fig. 6.

In the drawings, I have shown a pair of French windows 65 which are adapted to close against a jamb 66. Each of the windows 65 includes a frame 67 having a pane of glass 68 suitably mounted therein. A pivoted latching member 69 is secured to a widened portion 70 of the frame 67 of each of the windows 65. The latching members 69 each comprise a hub 71, which is pivotally mounted upon a bolt or stud 72 which is secured to and extends outwardly from the portion 70 of the frame 67, a latching arm 73, and an operating handle 74. In latching position, the latching arm 73 extends laterally from the hub 71 into engagement with the inner face of the jamb 66, and the operating arm 74 extends inwardly and downwardly from the hub 71.

In order to retain the latching members 69 in latching position, I provide a locking mechanism, generally indicated by the numeral 75, which includes a keeper 76 which is adapted to engage the arms 73 when they are in latching position and hold them against movement. The keeper 76 is secured to or may be formed integral with a lever 77 which is pivotally mounted upon a shaft 78 in a clevis 79 which is secured within a casing 80 by screws 81. The casing 80 consists of a base 82, a cover 83 and a rectangular frame 84, which are all rigidly secured together by screws 85. The casing 80 is rigidly secured to the jamb 66 by non-removable screws or rivets 86 which extend through suitable apertures in extension 87 of the base 82. A cylinder lock 88 is secured to the cover 83 by a nut 89 and extends into the casing 80. The lock 88 has a key-operated rotary plug 90 to which is secured a cam member 91 by a nut 93. The cam member 91 has a cam track 94 thereon which engages the inner end 95 of the lever 77. A spring 96 maintains the end 95 of the lever 77 against the cam track 94 as the cam 91 is rotated by the key-operated rotary plug 90.

When the high part 97 of the cam track 94 engages the inner end 95 of the lever 77, the keeper 76 is moved inwardly against the jamb 66 and envelops the latching arms 73 which prevents them from being moved out of engagement with the jamb 66, as is shown in Fig. 3. When the cam 91 has been rotated to the position shown in Fig. 4, the end 95 of the lever 77 is in engagement with the low part 98 of the cam track 94, and the keeper 76 is

swung inwardly away from the jamb 66 releasing the latching arms 73 so that they can be swung out of engagement with the jamb 66 to release the windows so that they can be opened.

From the foregoing it will be apparent to those skilled in this art that I have provided a very simple and efficient means for accomplishing the objects of my invention.

It is to be understood that I am not restricted to the specific construction of the embodiment shown and described herein, as various changes may be made thereto within the spirit of the invention.

What is claimed is:

A latching mechanism for securing a window frame closed against a jamb wherein a latching arm is pivotally mounted on said window frame to be moved in a plane parallel to said jamb into and out of engagement with said jamb, said latching mechanism comprising a casing to be mounted on said jamb, a catch pivotally mounted in said casing for movement in a plane normal to said jamb to engage said latching arm when depressed toward said jamb to hold said latching arm

5 against movement, a cylinder lock in said casing having a rotary plug, a rotary cam secured to said plug, said cam engaging said catch and operative to hold said catch in engagement with said latching arm, and spring means operative to withdraw

said catch from engagement with said latching arm when released by said cam.

NEIL O. HOLMSTEN.
